(No Model.)

B. S. SEAMAN.
BICYCLE SADDLE.

No. 591,145.

Patented Oct. 5, 1897.

UNITED STATES PATENT OFFICE.

BENJAMIN S. SEAMAN, OF CANTON, OHIO.

BICYCLE-SADDLE.

SPECIFICATION forming part of Letters Patent No. 591,145, dated October 5, 1897.

Application filed July 17, 1896. Serial No. 599,476. (No model.)

To all whom it may concern:

Be it known that I, BENJAMIN S. SEAMAN, a citizen of the United States, and a resident of Canton, county of Stark, State of Ohio, have invented new and useful Improvements in Bicycle-Saddles, of which the following is a full, clear, and exact description, reference being had to the accompanying drawings, making part of this specification.

10 My invention relates to improvements in bicycle-saddles; and it consists of certain features of construction and combination of parts, as will be hereinafter described and claimed.

15 The object of the invention is to provide means for securing the saddle to the post.

Figure 1 is a perspective view of a saddle which may be provided with my improved clamp. Fig. 2 is a plan view from below. 20 Fig. 3 is a longitudinal section. Fig. 4 is a perspective of saddle-frame. Fig. 5 is a similar view of pommel-frame. Fig. 6 is a similar view of tension-screw. Fig. 7 is a similar 25 view of a cross-bar by which the seat-leather is secured to the frame. Fig. 8 is a longitudinal section through the seat-clamp. Fig. 9 is a side view of the clamp. Fig. 10 is a perspective of the clamp with jaws and nuts removed. Fig. 11 is a similar view of the 30 side jaw-piece. Fig. 12 is a similar view of the outside jaw-piece, and Fig. 13 is a similar view of the tightening-nut.

The saddle-frame is formed of the cantle A, the pommel-support B, and the connecting branches of the spring C and adjusting-screw D, supported in the socket E. Over this frame is placed and properly secured a soft rawhide cover F, the rear end portion of which is secured to the cantle A and the front end 35 to the pommel-frame B, which is supported on the front end of the adjusting-screw D. For the purpose of ventilation the rawhide is perforated, as shown. To curl or draw in the lower edges or sides of the rawhide, a buckle

and strap G are secured to the sides and may 45 be drawn inwardly, as shown. Over this rawhide is placed the seat-leather H, secured in position at its front end by the bar J and at the rear end by lacing to the cantle A, as shown, thus forming a soft or yielding saddle. 50

To secure the saddle to the post K, a clamping-head, as L, is provided, having prongs a, having a kerf b in each of said prongs, in which is placed a clamping-bit c, a portion of which is adapted to pass through the wall of 55 the clamp L to engage the post K. The outer face of said bit c is adapted to embrace the wire spring C. A clamping-bit, as d, having outwardly-projecting wing portions e and a face f, adapted to embrace the wire spring C, 60 is placed in the kerf b to engage the outer side of the wire spring. On the ends of the prongs a is provided a screw-thread on which is turned the binding-nut M, resting on the wings e of the bit d, which latter is drawn 65 against the wire C and bit c, clamping the wire and driving a portion of the bit c against the post K, thereby securing the parts in desired adjustment.

To adjust the saddle on the post K or to adjust the spring in the clamp, the nuts M may be slackened and the saddle or clamp adjusted and the nut turned on again to secure the parts in desired adjustment. 70

What I claim is—

In a bicycle-saddle and in combination with post K, and spring C, of the clamp L, having kerfed prongs a, in which are placed clamp-bits c and d, the former adapted to engage the post, the latter in conjunction with the 80 former to engage the spring C and the tightening-nut M, substantially as set forth. 75

In testimony whereof I have hereunto set my hand this 8th day of June, A. D. 1896.

BENJAMIN S. SEAMAN.
